PIPE ROTATING DEVICE FOR OIL WELLS

Theodor R. Munsinger, Meeker, Colo.

Application November 29, 1948, Serial No. 62,528

3 Claims. (Cl. 255—35)

1

This invention relates to a pipe rotating device, and is more particularly applicable for use in oil well drilling and servicing so as to reduce the time and labor usually required for screwing and unscrewing well pipe, casing, drill pipe, etc.

The principal object of the invention is to provide a device of this character which will be exceedingly positive and rapid in operation; which will not interfere in any way with the usual oil well operations, and which can be quickly and easily brought into and out of position for use.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawings:

Fig. 1 is a side view of the lower portion of a typical oil well derrick, illustrating the invention in place thereon;

Fig. 2 is a plan view of the improved pipe rotating device, illustrating it in position for use;

Fig. 3 is a side view thereof;

Fig. 4 is a cross-section, taken on the line 4—4, Fig. 3; and

Fig. 5 is a detail cross section taken on the line 5—5, Fig. 2.

In Fig. 1 conventional elements of a drilling rig are designated by numeral as follows: derrick 10, platform 11, rotary table 12, wedges 13, pipe tongs 14, casing 15, and coupling 16.

The improved pipe rotating device is preferably supported in two parallel channel slide track members 17 supported from the derrick 10 upon suitable bracket members 18 and cross beams 19. The pipe rotating mechanism is mounted on an elongated frame 20 which is slidably mounted in and between the track members 17. Anti-friction rollers may be provided to assist the sliding movement of the frame if found desirable.

Two roller plates 22 and 23 are mounted on and project forwardly from the forward extremity of the frame 20, the plate 22 being above and the plate 23 being below the frame 20. The plates 22 and 23 are similar in contour and have curved portions extending forwardly on an arc so as to partially surround the axis of the casing 15. A hinge shaft 24 is vertically and rotatably mounted in the plates 22 and 23 on the center

2

line of the frame 20 and casing 15. Upper and lower swinging jaw plates 25 are hingedly mounted on the shaft 24 so that they may swing about the axis of the latter.

Two roller shafts 26 are mounted in the curved portion of the plates 22 and 23, and each carries a friction roller 27 positioned between the two roller plates. Two similar roller shafts 28 are mounted in the two swinging jaw plates 25, and each carries a friction roller 29 positioned between the two jaw plates. The rollers 27 and 29 may have any desired construction, as illustrated they comprise hub-like cores 48 covered with a suitable friction material, such as rubber, neoprene, canvas, leather, or the like, so that they will frictionally engage the surface of the casing 15.

The roller plates 22 and 23 also carry vertical gear shafts 30 positioned between the two roller shafts 26 and between the shafts 24 and 26. The two swinging jaw plates 25 also carry similarly positioned gear shafts 31. Each of the gear shafts 30 and 31 is provided with a pinion gear 33. The pinion gears 33 mesh with drive gears 32 mounted on the cores 48 of the two adjacent friction wheels so as to provide a continuous gear train along the plates 22 and 23 and along the jaw plates 25.

The two innermost pinion gears 33 mesh with a power gear 34 keyed on the hinge shaft 24 by means of a shaft key 51. The shaft 24 is driven from a worm gear 35, which in turn is driven from a worm 36. The worm 36 is mounted on a worm shaft 37 driven from any suitable drive motor 38 through the medium of transmission gears or a transmission chain enclosed in a housing 39. The motor 38 is mounted on the frame 20 and the shaft 37 is supported in bearings 49 on the frame 20 so that the entire assembly will move as a unit.

The jaw plates 25 are swung about the axis of the shaft 24 by means of a hydraulic plunger 40 actuated from a double acting hydraulic cylinder 41. The cylinder 41 is mounted on a hinge pin 42 on the frame 20, and the plunger 40 is mounted on a hinge shaft 43 extending between the two jaw plates 25. Fluid is admitted to the cylinder 41 through the medium of hydraulic tubes 44.

The frame 20 is moved along the track members 17 by means of a second hydraulic plunger 45 actuated from a second hydraulic cylinder 46 to which fluid is admitted through hydraulic tubes 47. The hydraulic cylinder is mounted on one of the track members 17 and the plunger 45 connects with a plunger shaft 50 extending between

the plates 22 and 23. It will be noted that one side of the channel track structure 17 is cut away, as shown at 21, to provide clearance for the mounting of the hinge pin 42 when the plunger 45 is retracted.

Let us assume that casing is being withdrawn from the well. The casing is elevated in the derrick until the coupling 16 rises above the rotary table 12. The string of casing is then locked by means of wedges 13, and the length of casing in the derrick is unloosened from the coupling 16 by means of the tongs 14.

The hydraulic plunger 45 is then actuated to force the pipe rotating device against the casing, as shown in Fig. 2, and the hydraulic plunger 40 is actuated to clamp the rollers 27 and 29 tightly against the casing. The motor 38 is then started so as to rotate the rollers and spin the suspended length of casing from the coupling 16.

The jaw plates are then opened by actuation of the plunger 40, and the device is withdrawn by actuation of the plunger 45 to allow the freed casing to be swung to the stored position in the derrick.

It often happens that when the lengths of drill stem, tubing, or casing, are swung into position over the string, the threads in the couplings will be damaged, due to the difficulty of lowering the lengths accurately into the coupling. This damage is avoided by the use of the present invention, for the device can be installed so that when in operating position, it will be concentric with the well string, so that the mere act of swinging a length into the device will automatically center the length over the coupling so that it can be spun therein without damage to the threads.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. A pipe rotating device for use on oil wells and the like comprising: an elongated, horizontal frame; arcuate roller plates extending from the extremity of said frame; a vertically positioned center hinge shaft carried by said roller plates; arcuate jaw plates swingingly mounted on said hinge shaft, said roller plates and said jaw plates extending partially about the pipe to be rotated; roller shafts mounted in said roller plates and in said jaw plates in spaced-apart relation; rollers carried by said roller shafts and adapted to frictionally engage the pipe; hydraulic means connected between said jaw plates and said frame so that when actuated, said means will swing said jaw plates toward the axis of said pipe; gear shafts positioned intermediate said roller shafts; driven gears mounted on said rollers for rotating the latter; pinion gears mounted on said gear shafts in mesh with said driven gears and intermediate each pair of the latter; a power gear

mounted on said hinge shaft in mesh with the adjacent pinion gears on said roller plates and on said jaw plates; and means for rotating said hinge shaft to cause said power gear to rotate said rollers in a common direction.

2. A pipe rotating device for use on oil wells and the like comprising: an elongated, horizontal frame, arcuate roller plates extending from the extremity of said frame; a vertically positioned center hinge shaft carried by said roller plates; arcuate jaw plates swingingly mounted on said hinge shaft, said roller plates and said jaw plates extending partially about the pipe to be rotated; roller shafts mounted in said roller plates and in said jaw plates in spaced-apart relation; rollers carried by said roller shafts and adapted to frictionally engage the pipe; hydraulic means connected between said jaw plates and said frame so that when actuated, said means will swing said jaw plates toward the axis of said pipe; gear shafts positioned intermediate said roller shafts; driven gears mounted on said rollers for rotating the latter; pinion gears mounted on said gear shafts in mesh with said driven gears and intermediate each pair of the latter; a power gear mounted on said hinge shaft in mesh with the adjacent pinion gears on said roller plates and on said jaw plates; a drive shaft extending longitudinally of said frame; and means for transmitting the rotation of said drive shaft to said hinge shaft to rotate said rollers.

3. A pipe rotating device for use on oil wells and the like comprising: an elongated, horizontal frame; arcuate roller plates extending from the extremity of said frame; a vertically positioned center hinge shaft carried by said roller plates; arcuate jaw plates swingingly mounted on said hinge shaft, said roller plates and said jaw plates extending partially about the pipe to be rotated; roller shafts mounted in said roller plates and in said jaw plates in spaced-apart relation; rollers carried by said roller shafts and adapted to frictionally engage the pipe; means for simultaneously rotating all of said rollers in a common direction; track members slidably supporting said frame; and a hydraulically actuated plunger connected between said track members and said frame to move the latter longitudinally in said track members.

THEODOR R. MUNSINGER.
